CLAIM

The ornamental design for a OTF knife, as shown and described.

DESCRIPTION

FIG. 1 is a top perspective view of a OTF knife of my new design in a closed configuration.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a bottom perspective view thereof.

FIG. 9 is a perspective view of the OTF knife of FIG. 1 is an open configuration.

FIG. 10 is a front view thereof.

FIG. 11 is a rear view thereof.

FIG. 12 is a left side view thereof.

FIG. 13 is a right side view thereof.

FIG. 14 is a top view thereof.

FIG. 15 is a bottom view thereof; and,

FIG. 16 is a bottom perspective view thereof.

The broken lines depict portions of the OTF knife in which the design is embodied that form no part of the claimed design.

1 Claim, 10 Drawing Sheets
